UNITED STATES PATENT OFFICE.

GEORGE ALBERT LYON, OF PHILADELPHIA, PENNSYLVANIA.

AUTOMOBILE-BUFFER.

1,325,728.

Specification of Letters Patent. Patented Dec. 23, 1919.

Application filed May 22, 1917. Serial No. 170,129.

To all whom it may concern:

Be it known that I, GEORGE ALBERT LYON, a citizen of the United States, and resident of Philadelphia, Philadelphia county, Pennsylvania, have made a certain new and useful Invention Relating to Automobile-Buffers, of which the following is a specification, taken in connection with the accompanying drawing, which forms part of the same.

This invention relates especially to resilient or spring strip buffers for use on automobiles or other similar vehicles in which the transverse width of the buffer is adjustable and its rearwardly extending attaching members are also independently adjustably connected to the front or impact receiving members of the buffer so as to simultaneously adjust the buffer for attachment to vehicles having frame members of different width. It is also desirable in this connection to have the impact receiving members forwardly bowed and formed of uniformly curved contour and in this way thelapping contacts where one buffer member is connected to another may be concentrically curved which facilitates adjustment of the parts.

In the accompanying drawing showing in a somewhat diagrammatic way illustrative embodiments of the invention—

Figure 1 is a top view showing one embodiment; and

Fig. 2 is a similar view showing another form of the device.

The impact receiving member or front member of the buffer may be made of adjustable width by forming it of overlapping members which are adjustably connected together in any suitable way so that by adjusting the extent to which these members overlap at the central portion of the buffer the total width of the impact receiving member can be correspondingly varied. It is desirable to form these impact receiving members of resilient spring steel strips having many times as great vertical as horizontal rigidity which can be conveniently done by giving the strips of spring steel six or eight times as great a vertical width as their thickness in a horizontal direction as explained in greater detail in the Lyon Patent 1,198,246, of September 12, 1916. As indicated in Fig. 1, the impact receiving members 4, 10 may be adjustably connected by the clips 12, 13, such as described and shown in detail in

said patent, and in this way by having one of these clips adjacent one end 3 of the forward impact receiving member 4, for instance, its other end 5 may extend out a considerable distance beyond the end 9 of the other impact receiving member 10 so that the outer ends 5 and 8 of these members may be arranged at the desired distance apart determined by the vehicle to which the device is to be attached. It is also advantageous to have these impact receiving members bowed forwardly which increases the extent of their resilient yielding action under collision conditions and by making these members uniformly curved at least throughout their overlapping portions adjustment and connection of these two members may be correspondingly facilitated. The buffer may also comprise rearwardly extending attaching members preferably formed of similar vertically rigid and horizontally yielding spring strips and these attaching members may be formed with a rearward portion adapted to be rigidly secured to the frame of the automobile or other vehicle while their forwardly and outwardly curved portions 6, 7 are preferably formed with ends having substantially the same curvature as the adjacent parts of the impact receiving or front members so that they may be more readily secured thereto in adjusted position by suitable clips 11, 14. By making these connections adjustable the distance apart of the attaching members 1, 2, may be correspondingly varied to adapt the buffer for attachment to vehicles having frame or other supporting members at different distances apart.

Fig. 2 shows another arrangement in which the impact receiving members overlap so as to reinforce each other throughout the distance between the points at which the attaching members are secured, this making a stronger and stiffer form of buffer although correspondingly limiting the extent to which the width of the impact receiving members can be adjusted. These impact receiving members 17, 18, are as indicated preferably forwardly bowed and given a substantially uniform curvature and in this way they may be readily secured by suitable clips or connecting devices arranged at the desired distances apart so as to connect them in a vertically rigid manner and thus prevent rattling and displacement. The forward member 18 may have its end 19 pro-

ject outward from one side of the buffer as a single thickness end member while the other end 20 of this forward impact receiving member may be adjustably arranged with respect to the projecting end 21 of the rear impact receiving member 17 whose other end 22 may be arranged adjacent the connecting clip 25. If desired, this connecting clip may not only connect the two impact receiving members, but also secure thereto the forwardly and outwardly curved end 23 of the rearwardly extending attaching member 15. The other clip 26 which may if desired be of the same general type as shown in said patent may connect the other ends of the impact receiving members and secure thereto in a vertically rigid manner the forward end 24 of the attaching member 16. In this way the clips may be moved together somewhat when it is desired to adjust the width of the attaching members, this adjustment being of course independent of the adjusted width of the buffer secured by more or less varying the extent of overlap of the front members thereof.

This invention has been described in connection with a number of illustrative embodiments, forms, proportions, parts, arrangements, materials, method of connection and use, to the details of which disclosure the invention is not of course to be limited, since what is claimed as new and what is desired to be secured by Letters Patent is set forth in the appended claims.

1. The automobile buffer comprising two overlapping forwardly bowed impact receiving members of uniform curvature and formed of integral spring steel strips having many times greater vertical width than thickness to render them relatively rigid vertically while resiliently yielding in horizontal directions, connecting clips adjustably connecting said impact receiving members to form an adjustable width buffer front member having a reinforced central portion and outwardly extending projecting ends of reduced thickness, vertically rigid horizontally yielding attaching members adapted to be rigidly connected to a vehicle frame and formed with forwardly and outwardly curved portions having ends formed with substantially the same curvature as the adjacent parts of the impact receiving members and connecting clips adjustably securing the forward ends of said attaching members adjacent the ends of said impact receiving members to adjust the distance between them so that said attaching members can fit vehicle frames of different widths.

2. The automobile buffer comprising two overlapping forwardly bowed impact receiving members formed of integral spring steel strips having many times greater vertical width than thickness to render them relatively rigid vertically while resiliently

yielding in horizontal directions, connecting clips adjustably connecting said impact receiving members to form an adjustable width buffer front member having a reinforced central portion and outwardly extending projecting ends of reduced thickness, vertically rigid horizontally yielding attaching members adapted to be rigidly connected to a vehicle frame and formed with forwardly and outwardly curved portions having ends formed with substantially the same curvature as the adjacent parts of the impact receiving members and connecting devices adjustably securing the forward ends of said attaching members adjacent the ends of said impact receiving members to adjust the distance between them so that said attaching members can fit vehicle frames of different widths.

3. The automobile buffer comprising two overlapping impact receiving members having many times greater vertical width than thickness to render them relatively rigid vertically while resiliently yielding in horizontal directions, connecting devices adjustably connecting said impact receiving members to form an adjustable width buffer front member having a reinforced central portion and outwardly extending projecting ends of reduced thickness, vertically rigid horizontally yielding attaching members adapted to be rigidly connected to a vehicle frame and formed with forwardly and outwardly curved portions and connecting devices adjustably securing the forward ends of said attaching members adjacent the ends of said impact receiving members to adjust the distance between them so that said attaching members can fit vehicle frames of different widths.

4. The automobile buffer comprising overlapping forwardly bowed impact receiving members of uniform curvature having greater vertical width than thickness to render them relatively rigid vertically while resiliently yielding in horizontal directions, vertically rigid attaching members adapted to be rigidly connected to a vehicle frame and formed with outwardly curved forward connecting portions having ends formed with substantially the same curvature as the adjacent parts of the impact receiving members and connecting clips adjustably connecting said impact receiving members to adjust the width of the buffer and adjustably securing the forward ends of said attaching members adjacent the ends of said impact receiving members so that said attaching members can fit vehicle frames of different widths.

5. The automobile buffer comprising overlapping forwardly bowed impact receiving members having greater vertical width than thickness to render them relatively rigid vertically while resiliently yielding in horizon-

- tal directions, vertically rigid attaching members adapted to be rigidly connected to a vehicle frame and formed with forward connecting portions having ends formed with substantially the same curvature as the adjacent parts of the impact receiving members and connecting devices adjustably connecting said impact receiving members to adjust the width of the buffer and adjustably securing the forward ends of said attaching members adjacent the ends of said impact receiving members so that said attaching members can fit vehicle frames of different widths.
- 15 6. The automobile buffer comprising overlapping impact receiving members having greater vertical width than thickness to render them relatively rigid vertically while resiliently yielding in horizontal directions, vertically rigid attaching members adapted to be rigidly connected to a vehicle frame and formed with forward connecting portions and connecting devices adjustably connecting said impact receiving members to adjust the width of the buffer and adjustably securing the forward ends of said attaching members adjacent the ends of said impact receiving members so that said attaching members can fit vehicle frames of different widths.
- 20 7. The automobile buffer comprising two overlapping forwardly bowed impact receiving members of uniform curvature having greater vertical width than thickness to render them relatively rigid vertically while resiliently yielding in horizontal directions, vertically rigid horizontally yielding attaching members adapted to be rigidly connected to a vehicle frame and formed with outwardly curved forward connecting portions having ends formed with substantially the same curvature as the impact receiving member and connecting devices adjustably connecting the forward ends of said attaching members adjacent the ends of said impact receiving member so that said attaching members can fit vehicle frames of different widths.
- 25 8. The automobile buffer comprising two overlapping impact receiving members having greater vertical width than thickness to render them relatively rigid vertically while resiliently yielding in horizontal directions, vertically rigid horizontally yielding attaching members adapted to be rigidly connected to a vehicle frame and formed with outwardly curved forward connecting portions having ends formed with substantially the same curvature as the impact receiving member and connecting devices adjustably connecting the forward ends of said attaching members to the ends of the doubled reinforced portion of said impact receiving members and enable said attaching members to fit vehicle frames of different widths.
- 30 9. The automobile buffer comprising a forwardly bowed impact receiving member of uniform curvature and formed of integral spring steel strips having greater vertical width than thickness to render the same relatively rigid vertically while resiliently yielding in horizontal directions, said strips being arranged to form a reinforced central portion and outwardly extending projecting ends of reduced thickness, vertically rigid horizontally yielding attaching members adapted to be rigidly connected to a vehicle frame and formed with outwardly curved forward connecting portions having ends formed with substantially the same curvature as the impact receiving member and connecting devices adjustably connecting the forward ends of said attaching members adjacent the ends of said impact receiving member so that said attaching members can fit vehicle frames of different widths.
- 35 10. The automobile buffer comprising a forwardly bowed impact receiving member of uniform curvature and formed of spring steel strip having greater vertical width than thickness to render the same relatively rigid vertically while resiliently yielding in horizontal directions, vertically rigid horizontally yielding attaching members adapted to be rigidly connected to a vehicle frame and formed with outwardly curved forward connecting portions having ends formed with substantially the same curvature as the impact receiving member and connecting devices adjustably connecting the forward ends of said attaching members to the ends of said impact receiving member so that said attaching members can fit vehicle frames of different widths.
